UNITED STATES PATENT OFFICE.

MONTAGUE WILLIAM TUTT, OF LONDON, ENGLAND, ASSIGNOR OF ONE-HALF TO HULBURD ENGINEERING COMPANY, LIMITED, OF LONDON, ENGLAND.

FORCE PUMP.

Application filed July 25, 1922. Serial No. 577,405.

To all whom it may concern:

Be it known that I, MONTAGUE WILLIAM TUTT, a subject of the King of Great Britain, residing at St. Benet Chambers, Fenchurch Street, London, England, have invented new and useful Improvements in Force Pumps, of which the following is a specification.

This invention relates to force-pumps for compressing air or gas and feeding or dispensing liquids, of the kind wherein the pump body or cylinder is provided with two pistons or plungers differentially movable in the same direction, between which the charge is compressed, the rod of one plunger extending through the rod of the other plunger, the object of the invention being to provide an improved pump of this type in which the usual suction and back-pressure or non-return valves are dispensed with.

According to the invention the improved pump comprises a cylinder having inlet and outlet ports and a pair of plungers designed to be reciprocated in the said cylinder, the suction and compression space being provided between the said plungers. For this purpose the outer or upper plunger is maintained stationary for a portion, say one third, of each stroke whilst the lower or inner plunger is moving to draw in a charge

through the inlet port. The two plungers then move together for the remaining portion of the stroke which brings the induced charge opposite the outlet port. On the return stroke the outer or upper plunger is again held stationary for the first portion of the stroke, whilst the lower or inner plunger is drawn towards it to expel the charge through the outlet port after which the two plungers move together for the remaining portion of the stroke, when the operation begins de novo.

To operate the plungers, I advantageously make use of an arrangement in which the rod of the inner or lower plunger is reciprocated by a cross-head actuated by a crank on a crank shaft, and according to my present invention I also provide means for not only reciprocating the outer plunger, but also varying the period during which the outer

or temporarily stationary plunger is held stationary, so that the amount of charge which is drawn in between the two plungers and is discharged through the outlet is correspondingly varied, any residual charge being subsequently forced out through the inlet

port. In a suitable way of carrying out the invention, I employ a base plate upon which two superposed cam plates are centrally pivoted so that each can be independently adjusted in a rotary direction thereon, suitable means, such as concentric slots in the cam plates and securing bolts attached to the base plate, and extending through said slots, being provided for securing the cam plates in the position into which they are adjusted. These cam plates each carry a cam surface which bears against a roller attached to the upper or outer plunger, thereby holding the said plunger stationary for the period required. The outward or inward movement of the outer or upper plunger is positively effected by an extension piece on the cross-head while the return movement thereof is effected by the inner or lower plunger.

The pump may be either of the single acting type or of the tandem type, or in the form of two sets of tandem pumps, placed side by side, or two sets of four pumps may be arranged one on each side of the center line of the crank shaft, all the plungers being controlled by a single crank or cam.

My present invention is an improvement upon the form of pump illustrated in my former U. S. Patent #1,413,205, dated April 18, 1922.

To enable the invention to be fully understood, I will describe it by reference to the accompanying drawings, in which:

Fig. 1 is a sectional elevation of a force-pump having the improvements applied thereto, and

Fig. 2 is a view similar to Fig. 1, but showing the cam plates adjusted to expel a smaller quantity of the charge through the discharge outlet.

a indicates the upper or outer plunger, *b* the lower or inner plunger, and *c*, the cylinder in which the said plungers are reciprocated. *e* and *f* are respectively, the inlet and exhaust ports of the cylinder. *g* is a rod of the inner or lower plunger, *b*, which extends axially through the plunger *a*. *h*, illustrated in dotted lines, is the cross-head to which the outer end of the rod *g*, is attached, and which is reciprocated by means of a sliding block, *h'*, moving in a slot, *h''*, in the cross-head, the block being carried by crank pin, *i*, of the crank shaft, *i'*, *h'''* is the extension piece provided on the cross-head, *h*, for positively actuating the plunger *a*. The plunger, *b*

α , is prevented from rotating in the cylinder by means of a longitudinal groove, r , engaged by a set screw, q , in the cylinder wall, and j is a roller attached to the plunger, a , and coacting with the cam surfaces herein-after described.

k is a base plate or disc, keyed upon the crank shaft γ' , and l and m are, respectively, the superposed cam plates, which are centrally pivoted upon the base plate so that they can be adjusted in a rotary direction independently with respect thereto, the cam plates l and m carrying the cams γ' and m' respectively. o indicates a concentric slot formed in the cam plate, l , and o' is a similar slot formed in the cam plate m , said slots being engaged by bolts, p and p' , respectively which are provided with locking nuts to retain the cam plates in the positions to which they are adjusted.

Figure 1 shows the cam plates l and m set for the full capacity of the pump, the two plungers meeting at the discharge end of the stroke at the same moment that the cam roller j is released from the cam, the whole of the charge between the two plungers thus having been expelled through the outlet port f .

The pump operates as follows, that is to say, at the beginning of a stroke, the inner end of the plunger, a , is approximately coincident with the outer end of the inlet port, e , and the plunger, b , is in contact with the plunger, a . In this position of the parts, the roller, j , is just in contact with the inner surface of the cam, m' . As the crank shaft rotates in the direction of the arrow, the plunger, b , will be moved inwardly, the plunger, a , being held stationary by the cam, m' until the latter passes out of contact with the roller, during which period the movement of the plunger, b , has drawn a charge into the space between the plungers. For the remaining portion of the stroke, the two plungers move together, the inlet port being completely closed by the plunger, a . The continued rotation of the crank shaft then moves the plunger, b , upwardly while the plunger, a , is held stationary by the engagement of the roller, j , with the exterior of the cam, γ' , thereby expelling the fluid between the two plungers through the outlet port. This relative movement continues with this adjustment of the cams until the plunger, b , contacts with the inner end of the plunger, a , at which point the cam, γ' , leaves the roller, j , and for the remaining portion of the stroke, the two plungers move together until the cam m' again engages the roller j , when the operation begins de novo.

If now, the cam plates, l and m , be adjusted, to, say, the positions shown in Fig. 2, the cam roller, j , is released when the inner plunger, b , has completed only half its stroke, as shown in Fig. 2. The residual

portion of the charge remains between the plungers owing to the pressure prevailing at the outlet port and is carried upwards, and eventually discharged through the inlet port when the plungers close or come together. As will be understood, therefore, by suitably regulating the period during which the outer plunger is held by its cams in stationary position, the volume of charge drawn in between the plungers and the volume of feed or discharge through the outlet port can be varied to suit different requirements, the regulation being effected by the adjustment of either or both of the cam plates, l and m .

What I claim and desire to secure by Letters Patent is:—

1. A force pump comprising a cylinder having inlet and outlet ports, a pair of plungers reciprocable therein, means for retaining the upper or outer plunger stationary for a portion of the inward and downward strokes, and for moving the said plungers together for the remaining portions of the stroke so as to draw in a charge between the plungers, and expel it therefrom, the movement of one plunger being effected by the movement of the other plunger, and means for varying the time in the cycle of operation during which the upper or outer plunger is held stationary, to vary the capacity of the pump.

2. A force pump as claimed in claim 1, wherein the rod of the inner or lower plunger extends through the upper or outer plunger, and is reciprocated by a crank shaft which carries a pair of adjustable cam plates having each a cam surface, designed to engage and hold the upper or outer plunger, the inward and downward movements of which are effected by the inner plunger, and means for rotarily adjusting said cam plates with respect to each other and with respect to the cam shaft, to vary the capacity of the pump.

3. In a force pump, the combination with a cylinder having inlet and outlet ports, of a pair of plungers reciprocable therein, a crank shaft and crank connections from the crank to one of said plungers having a part extending through the other plunger and provided with means for engaging and moving the latter plunger in one direction, its movement in the opposite direction being effected by the crank actuated plunger, means operable in timed relation with the crank shaft for holding the second mentioned plunger stationary during portions of the reciprocating movements of the first mentioned plunger, means for varying the operative period of said holding means with respect to the crank shaft, to vary the capacity of the pump.

4. In a force pump, the combination with a cylinder having inlet and outlet ports, of a pair of plungers reciprocable therein, a

- crank shaft and crank for operating both plungers, connections from said crank to one plunger, provided with a part extending through and having a sliding engagement 5 with the other plunger and provided with means for positively operating the latter plunger in one direction, its movement in the opposite direction being effected by the crank actuated plunger, a pair of separate 10 cams on the crank shaft provided with cam faces for holding the second mentioned plunger stationary during a portion of the reciprocating movements of the first mentioned plunger in both directions, a part 15 connected with the second mentioned plunger for operatively engaging said cams, and means for adjusting said cams independently in a rotary direction with respect to the crank shaft, to vary the capacity of the 20 pump.
5. In a force pump the combination with a cylinder, having inlet and outlet ports, or a pair of plungers reciprocable therein, a plunger rod connected to one of said plungers 25 and extending through and having a sliding engagement with the other plunger, said rod having a part for engaging and moving the latter plunger, a crank shaft and crank, said crank being operatively 30 connected to said plunger rod, a base plate carried by said shaft, independent cam plates
- provided with cams, a roller on the second mentioned plunger for engaging said cams to hold the plunger stationary during portions of the movement of the other plunger 35 in both directions, and means for independently adjusting said cams with respect to and securing the same to said base plate.
6. In a force pump, the combination with a cylinder having inlet and outlet ports, of 40 a pair of plungers reciprocable therein, a plunger rod connected to one of said plungers and extending through and having a sliding engagement with the other plunger, said rod having a part for engaging and 45 moving the latter plunger, a crank shaft and crank, a cross-head secured to said plunger rod and engaging a part connected with said crank, a rotary base plate carried by the crank shaft, a pair of cam plates 50 each provided with a cam surface and having a slotted portion, bolts extending through said slotted portions and through the base plate for adjustably securing said cam plates to the base plate, and a friction 55 roller connected with said second mentioned plunger for engaging said cams to hold the said plunger stationary during a portion of the movement of the first mentioned plunger in both directions.

MONTAGUE WILLIAM TUTT.
